US0D1023313S

(12) **United States Design Patent** (10) **Patent No.:** **US D1,023,313 S**
(45) **Date of Patent:** **** Apr. 16, 2024**

(54) **INSTRUMENT FOR MEASURING
EYE-HEALTH CHARACTERISTICS**

(71) Applicant: **Zeavision LLC**, Chesterfield, MO (US)

(72) Inventor: **Joshua J. Park**, Riverside, CA (US)

(73) Assignee: **ZEAVISION LLC**, Chesterfield, MO (US)

(**) Term: **15 Years**

(21) Appl. No.: **29/868,694**

(22) Filed: **Dec. 12, 2022**

Related U.S. Application Data

(63) Continuation-in-part of application No. 18/064,052, filed on Dec. 9, 2022, which is a continuation-in-part of application No. 17/304,274, filed on Jun. 17, 2021.

(57) **CLAIM**

The ornamental design for an instrument for measuring eye-health characteristics, as shown and described.

DESCRIPTION

FIG. 1 is a first perspective view of an instrument for measuring eye-health characteristics;

FIG. 2 is a second perspective view of the instrument for measuring eye-health characteristics of FIG. 1;

FIG. 3 is a rear view of the instrument for measuring eye-health characteristics of FIG. 1;

FIG. 4 is a right side view of the instrument for measuring eye-health characteristics of FIG. 1;

FIG. 5 is a front view of the instrument for measuring eye-health characteristics of FIG. 1;

FIG. 6 is a left side view of the instrument for measuring eye-health characteristics of FIG. 1;

FIG. 7 is a top view of the instrument for measuring eye-health characteristics of FIG. 1; and,

FIG. 8 is a bottom view of the instrument for measuring eye-health characteristics of FIG. 1.

In the drawings, the broken lines are for the purpose of illustrating portions of the instrument for measuring eye-health characteristics which form no part of the claimed design.

1 Claim, 5 Drawing Sheets
